Primary Examiner — Vy N Koenig*Assistant Examiner* — Kimberly Barnes(74) Attorney, Agent, or Firm — Shook, Hardy and Bacon L.L.P.(57) CLAIM

The ornamental design for a garment, as shown and described.

DESCRIPTION

FIG. 1 is a front view of a garment showing our new design; FIG. 2 is a first side view thereof; FIG. 3 is a second side view thereof; and, FIG. 4 is a front perspective view thereof.

The unevenly broken lines represent a boundary that forms no part of the claimed design. The evenly broken lines represent portions of the garment that form no part of the claimed design.

1 Claim, 4 Drawing Sheets(56)
